UNITED STATES PATENT OFFICE.

JOHN Y. PARKE, OF PHILADELPHIA, PENNSYLVANIA.

ELECTRIC GAS-LIGHTER.

SPECIFICATION forming part of Letters Patent No. 400,479, dated April 2, 1889.

Application filed June 15, 1888. Serial No. 277,209. (No model.)

To all whom it may concern:

Be it known that I, JOHN Y. PARKE, a citizen of the United States, residing at Philadelphia, Philadelphia county, State of Pennsylvania, have invented certain new and useful Improvements in Electric Gas-Lighters, of which the following is a full, clear, and exact specification.

My invention relates to electric gas-lighting devices, and more particularly to that class which is generally provided with a pendant adapted to turn the cock permitting and stopping the flow of gas, and operating a spark device arranged at or near the tip of the burner to ignite the gas. Heretofore many such devices have been made, most of which are wasteful of the electric current, in that they operate to produce sparks at the burner-tip when not needed.

It is the object of my invention to produce a gas-lighting device which operates only to produce a spark when the gas is turned on; and to this end my invention consists in the construction and arrangement of parts, substantially as hereinafter set forth, and illustrated in the accompanying drawings, in which—

Figure 1 is a front view showing the position of the parts at or about the moment the gas is permitted to flow and the spark produced. Fig. 2 is a similar view showing the parts returning to their normal position. Fig. 3 is a side view showing the position of the parts as the gas is being turned off, and Fig. 4 is an enlarged view of the feathering cam.

The burner 1 may be of any desired construction, and is provided at or near its tip with a stationary or fixed electrode, secured as usual. A cock, 3, controls the flow of the gas to the burner by being moved to alternately open and close the passage, it being provided with one or more openings corresponding to the passage.

Mounted on the stem of the cock is a lever, 4, to which the ordinary pendant may be attached, and a spring, 5, normally holds it in an elevated position when not being operated. Attached to or connected with this lever is an arm, 6, carrying the movable electrode 7. This electrode is shown as being in the form of a spring, a portion of which is coiled around

the rod or carrier 8, and the other portion extends laterally, so as to be brought into contact with the fixed electrode with a wiping motion when it is desired to produce a spark. 55 This rod or carrier 8 is mounted on the arm 6 in any suitable way, and I have shown the arm provided with bearing-pieces 9 10, struck up or formed in one piece with the arm. A spring, 11, which may be an extension of the 60 electrode, if desired, tends to hold the arm in the position shown in Fig. 1. The lower end of the arm is bent or formed into a finger, 12, which serves as a pawl-bearing upon the cam-shaped ratchet 13, which is secured to the cock. 65 To operate it in turning on or off the gas. This ratchet is provided on its face with a series of cam-shaped projections, forming teeth or notches of varying depth, each alternate notch 14 being shown as deeper than its intervening notches 15; or, as shown at 19, the deeper notches may extend entirely through the edge of the cam to form slots. When the lever 4 is depressed, the gas being turned off, it operates to vibrate the arm 6, carrying the 70 movable electrode, and the finger 12 of the carrier 8 engages with one of the deeper notches, 14, of the cam or ratchet and moves the cock, so that one of its passages corresponds with the passages of the burner, permitting the gas to flow, and, as the arm is carried by the stationary electrode, the movable electrode 7 engages therewith and wipes across the same, producing a spark nearly at the end of its movement and just as the gas 75 flows through the burner, so that it will be instantly ignited. The lever is now returned to its normal position by the spring 5, and as the finger 12 moves back across the face of the cam it rides up over one of the projections 16 and causes the rod or carrier to be turned slightly on its axis, or, in other words, to be feathered, so that as the movable electrode passes the fixed electrode it will not come in contact therewith, but is feathered, 80 so as to pass in front thereof, as shown in Fig. 3. When it reaches its normal position, the finger engages one of the more shallow notches, 15, and when the lever is operated to turn off the gas to extinguish the same the 85 finger engaging with this shallow notch of the cam or ratchet propels the same to turn 90

100

the cock; but the notch does not permit the movable electrode to be turned sufficiently to engage with the fixed electrode, and it passes by in front thereof without engagement, and when the lever is returned again to its normal position by the spring the finger, as before, passes over the cam-surface and causes the carrier 8 to again be turned or feathered, so that the movable electrode 10 does not contact with the fixed electrode. It will thus be seen that the arm 6 reciprocates past the stationary electrode both when the cock is operated to permit the flow of gas and to stop it; but owing to the peculiar formation of the cam or ratchet the movable electrode is not permitted to engage with the fixed electrode but once, or at each second reciprocation, and that at the time when the cock is moved to permit the flow of gas. At 20 other times the movable electrode is held so as to pass in front of the fixed electrode by the feathering operation, as before set forth.

While I have illustrated what I consider to be the best embodiment of my invention, it is evident that the details of construction and arrangement may be varied without departing from the spirit thereof, the distinguishing feature of which consists in preventing the movable electrode making contact with the 30 fixed electrode except when the gas is turned on by means of the feathering operation of the electrode-carrier.

By this mode of operation it will be seen that the battery-power is used only when it is effective in lighting the gas, and during the other movements of the devices the electrodes do not operate.

I have used the term "feathering carrier" herein to describe a carrier having a movement substantially like the movement of an oar, in that when the moving electrode is passed by the fixed electrode the first time it comes in contact therewith; but when it is again passed by in the same direction the carrier is turned on its axis or feathered, so that the electrode will not contact with the fixed electrode.

What I claim is—

1. An electric gas-lighter having a movable

electrode adapted to be brought into contact 50 with another electrode to create a spark, and a feathering carrier for the electrode, arranged to prevent contact between the electrode except when the gas is turned on, substantially as described.

2. An electric gas-lighter having a movable electrode adapted to make contact with another electrode to produce a spark, a lever for moving the first electrode, and a feathering electrode-carrier controlling the contact between the electrodes, substantially as described.

3. An electric gas-lighter having a movable electrode adapted to make contact with another electrode, a lever for moving the first 65 electrode, a feathering carrier for the movable electrode, and a cam for controlling the position of the carrier, substantially as described.

4. An electric gas-lighter having a reciprocating electrode and a stationary electrode, a 70 feathering carrier for the movable electrode, and a cam controlling the carrier, the said cam also operating to move the cock controlling the flow of gas, substantially as described.

5. In an electric gas-lighter, a stationary 75 electrode, a cock, a ratchet-cam secured to the cock, a lever, and a movable electrode mounted on a carrier and controlled by the cam, substantially as described.

6. In an electric gas-lighter, a moving arm 80 and a feathering electrode-carrier mounted on said arm in bearings formed integral with the arm, substantially as described.

7. In an electric gas-lighter, a feathering electrode-carrier and a controller therefor 85 provided with projections on its side and notches on its edge, substantially as described.

8. In an electric gas-lighter, the combination, with a fixed electrode, of a feathering moving electrode, substantially as described. 90

In testimony whereof I have signed my name to this specification in the presence of two subscribing witnesses.

JOHN Y. PARKE.
